WEAR PLATE ASSEMBLY

Willard J. Fendner, Pittsburgh, Pa., assignor to
Frederic Schaefer, Pittsburgh, Pa.

Application April 4, 1936, Serial No. 72,755

6 Claims. (Cl. 188—209)

This invention relates to wearing shoes for receiving and supporting brake hangers in railway truck frame brackets.

Railway brake hangers are generally connected to truck frame brackets through the medium of plates or shoes mounted in the brackets for receiving the wear resulting from movement of the hangers therein. As these shoes are intended to be replaceable when worn, it is highly desirable that they be readily insertable into, and removable from, the cast truck frame brackets, the shoe-receiving slots of which vary somewhat in size. To allow for this variation in size, wearing shoes are made small enough to enter the smallest bracket slots encountered. Accordingly, in many cases the shoes fit loosely in the bracket slots where they vibrate and rattle. This causes the engaging surfaces of the brackets and shoes to wear rapidly, thereby permitting greater relative movements and consequently greater wear.

It is among the objects of this invention to provide a wearing shoe which can be easily inserted into and removed from bracket slots of different sizes, and which is tightly held in place in such brackets so as to substantially eliminate vibration and wear between their opposed surfaces.

According to this invention a wearing shoe, the inner portion of which is provided with a brake hanger seat, is mounted in the usual manner in a slot in a bracket projecting laterally from a railway truck frame. Resilient means, preferably in the form of a coil spring, is associated with the bracket and shoe for holding the latter tightly against the bracket to prevent wear of the engaging surfaces of the shoe and bracket due to vibration between them. The bracket and shoe are provided with the usual openings in which a fastening member, such as a bolt or cotter pin, is disposed for detachably locking the shoe in the bracket slot. Preferably, the spring is compressed between the shoe and the head of the fastening member.

The invention is illustrated in the accompanying drawing in which Fig. 1 is a transverse section through the top chord of a railway truck frame, showing in elevation a brake hanger connected to the hanger bracket by a wearing shoe in accordance with this invention; Fig. 2 is an enlarged fragmentary view taken on the line II—II of Fig. 1; Fig. 3 is a plan view of the wearing shoe taken on the line III—III of Fig. 2; and Fig. 4 is a vertical section through the shoe and hanger bracket taken on the line IV—IV of Fig. 2.

Referring to Figs. 1 and 2 of the drawing, a

bracket 1 projects laterally from the top chord 2 of a railway truck frame. The free end of the bracket extends downwardly and is provided with laterally projecting upper and lower parallel walls 3 extending longitudinally of the truck frame and forming a slot 4 open on three sides. This slot is for the purpose of receiving the upper yoke of a brake hanger 5. To prevent the hanger from wearing the bracket, a wearing plate or shoe 6 is detachably mounted in the slot with its inner end provided with a concave hanger seat 7. To aid in centering the shoe in the slot and to prevent the side arms of the hanger from wearing the bracket, the shoe is preferably provided at the ends of seat 7 with down-turned flanges 8 that overlap the underlying portion of the bracket. To decrease the weight of the shoe, save metal, and make it feasible to punch fastener-receiving holes 9 and 10 therethrough, its outer portion is originally made relatively long and thin and is then punched and bent upwardly and backwardly to form a U-shape portion having upper and lower legs for substantially engaging both walls 3 of the bracket. This outer portion of the shoe is preferably strengthened by bosses 11 integral therewith.

To lock the shoe in bracket slot 4, the upper and lower walls of the bracket are provided with openings 12 and 13 in axial alignment with shoe openings 9 and 10. A suitable retaining member 14 is detachably disposed in these four openings, and if a bolt 14 is used the nut 15 is preferably locked in place as by means of a metal strip 16 through one end of which the bolt extends and the other end of which is turned upwardly against the end of the lower wall of the bracket. After the nut has been tightened, the adjacent end of the locking strip is bent downwardly as shown in Fig. 2 to prevent the nut from turning and working loose. Bosses 11 add to the bolt-engaging surfaces of the shoe to reduce its wear.

It is a feature of this invention that the wearing shoe is held in the bracket slot in such a manner as to substantially eliminate vibration between them, and consequent wear of their engaging surfaces. This is preferably accomplished by means of a resilient member associated with the bracket and the shoe for holding the shoe firmly against the bracket at all times. As shown in Fig. 2, the resilient member is preferably in the form of a coil spring 21 encircling the upper portion of bolt 14. The upper bolt-receiving openings 9 and 12 of the bracket and shoe, respectively, are of materially greater diameter than the bolt so as to provide an annular space be-

tween the bolt and the walls of those openings for the reception of the coil spring. Consequently, the spring engages the upper surface of lower boss 11, extends upwardly through the upper portion of the shoe and the upper wall of the bracket and engages the bottom of the bolt head or a washer 22 at that point.

When nut 15 is tightened on the bolt the washer is drawn downwardly until it engages the top of the bracket. This compresses the coil spring between the washer and the lower portion of the shoe, and, consequently, the spring presses the wearing shoe firmly against the lower wall of the slot whereby vibration of the shoe in the bracket 15 and the wear attendant thereon is prevented.

When a wearing shoe is tightly and firmly held against vibration in a hanger bracket by a coil spring as disclosed herein, the life of both the shoe and the bracket is materially lengthened.

20 This is because the substantial elimination of relative movements between the shoe and bracket also substantially eliminates wear of their engaging surfaces. Furthermore, if a nut lock is not used, or if the lock is not properly applied, 25 the load put on the nut by the compressed coil spring tends to prevent the nut from working loose from the bolt.

According to the provisions of the patent statutes, I have explained the principle and construction of my invention, and have illustrated and described what I now consider to represent its best embodiment. However, I desire to have it understood that, within the scope of the appended claims, the invention may be practiced 35 otherwise than as specifically illustrated and described.

I claim:

1. The combination with a brake hanger bracket connected to a railway truck frame and having upper and lower walls forming a slot open on three sides, of a wearing shoe mounted in said slot with its inner portion provided with a brake hanger seat, a coil spring associated with said bracket and constraining said shoe against said lower wall of the bracket, and means for retaining said shoe in said bracket.

2. The combination with a brake hanger bracket connected to a railway truck frame and having upper and lower walls forming a slot open on three sides, of a wearing shoe mounted in said slot with its inner portion provided with a brake hanger seat, a coil spring disposed in said slot and bearing against said shoe to constrain it against said lower wall of the bracket, and means for retaining said shoe in said bracket slot.

55 3. The combination with a brake hanger

bracket connected to a railway truck frame and having upper and lower walls forming a slot open on three sides, of a wearing shoe mounted in said slot with its inner portion provided with a brake hanger seat, a coil spring disposed in said slot and bearing against said shoe for biasing it against said lower wall of the bracket, said bracket walls and shoe being provided with openings aligned with the axis of said coil spring, and a retaining member extending through said openings and said spring for locking the shoe in the bracket slot.

4. The combination with a brake hanger bracket connected to a railway truck frame and having upper and lower walls forming a slot open on three sides, of a wearing shoe mounted in said slot with its inner portion provided with a brake hanger seat, said bracket walls and shoe being provided with aligned openings, a headed fastening member disposed in said openings for locking the shoe in the bracket slot, and resilient means compressed between said shoe and the head of said fastening member.

5. The combination with a brake hanger bracket connected to a railway truck frame and having upper and lower walls forming a slot open on three sides, of a wearing shoe mounted in said slot with its inner portion provided with a brake hanger seat, said bracket walls and shoe being provided with aligned openings, a headed fastening member disposed in said openings for locking the shoe in the bracket slot, the opening in said upper wall of the bracket being larger than said fastening member, and a coil spring encircling said fastening member in said enlarged opening and being compressed between said shoe and the head of the fastening member.

6. The combination with a brake hanger bracket connected to a railway truck frame and having upper and lower walls forming a slot open on three sides, of a wearing shoe mounted in said slot with its inner portion provided with a brake hanger seat, the outer portion of said shoe being substantially U-shape with one leg engaging the lower wall of the slot and the other leg substantially engaging the upper wall thereof, said bracket walls and shoe legs being provided with aligned openings, a bolt disposed in said openings, a nut on the lower end of the bolt, said openings in said upper wall of the bracket and upper leg of the shoe being materially larger than said bolt, and a coil spring encircling said bolt and compressed between said lower leg of the shoe and the head of the bolt.

55 WILLARD J. FENDNER.
